[57] CLAIM

The ornamental design for a ski case, as shown and described.

DESCRIPTION

FIG. 1 is a front perspective view of a ski case showing my new design;

FIG. 2 is a top plan view thereof;

FIG. 3 is a side elevational view thereof;

FIG. 4 is a bottom plan view thereof;

FIG. 5 is an opposite side elevational view thereof;

FIG. 6 is an end elevational view thereof;

FIG. 7 is an opposite end elevational view thereof; and,

FIG. 8 is a front perspective view of a second embodiment of a ski case showing my new design, the top, sides, bottom and ends are substantially the same as FIGS. 1-7, the distinguishing characteristic being the expanded width.

FIG. 1

FIG. 2

FIG. 3

FIG. 4

FIG. 5

FIG. 7

FIG. 6

FIG. 8
